CLAIM

The ornamental design for picture hanger, as shown and described.

DESCRIPTION

FIGS. 1 and 2 are respectively front and rear elevational views thereof;

FIGS. 3 and 4 are respectively top and bottom plan views thereof;

FIGS. 5 and 6 are respectively left side elevational views thereof, the side opposite being a mirror image; FIG. 7 is a front, top and right side perspective views thereof; and

FIG. 8 is a left side, top and front perspective view thereof.

The broken line showing of a nail in FIG. 5 and a picture wire in FIG. 6 is for illustrative purposes only and forms no part of the claimed design.

Fig. 1.Fig. 5.Fig. 4.Fig. 2.Fig. 6.Fig. 3.*Fig. 7.**Fig. 8.*
